UNITED STATES PATENT OFFICE.

MORRIS MATTSON, OF NEW YORK, N. Y.

WATER-BAG.

SPECIFICATION forming part of Letters Patent No. 241,390, dated May 10, 1881.

Application filed April 4, 1881. (Model.)

To all whom it may concern:

Be it known that I, MORRIS MATTSON, of New York, in the county of New York and State of New York, have invented certain new and useful 5 Improvements in Water-Bags; and I do hereby declare the following to be a full, clear, and exact description of the invention, such as will enable others skilled in the art to which it pertains to make and use it, reference being had 10 to the accompanying drawing, which forms part of this specification.

My invention relates to an improvement in water-bags; and it consists in attaching one or more handles, made of any suitable rigid material, to the edge or edges of the bag, near its mouth, whereby the bag can be more conveniently held while being filled, as will be more fully described hereinafter.

The object of my invention is to dispense with 20 the usual flexible straps which are attached to the bags for convenience in carrying them, but which cannot be used conveniently or safely when the bag is being filled with hot water; and also to provide the bag with rigid handles 25 near its mouth, whereby the bag can be filled as easily and with as much safety with hot water as any other small-necked vessel.

The accompanying drawing represents a side elevation of my invention, partly in section.

30 A represents an ordinary water-bag, such as is in common use, and which is provided with the funnel B at its upper end as a means of filling the bag with water. In the neck of the bag is secured the short tube C, which has a screw-thread cut on its end to receive a cap, D, whereby the bag is securely sealed after it is filled. I prefer that the cap D shall be made of hard rubber, as it does not become heated unduly when the bag is filled with hot water, 40 and therefore can be handled in tightening the screw without burning the fingers.

Heretofore these water-bags have been provided with flexible straps for handles, which answer well enough to merely carry the bags 45 or to hang them up, but which are of little or no service in holding the bags while they are being filled. The trouble with these bags has always been that persons in filling them with

hot water are liable to have their hands scalded by the hot water or steam, or both together, 50 because the bags have never been provided with suitable handles by which the bag could be held firmly and steadily while being filled. As long as the bag is flexible there is no means of holding its upper extremity with any safety, 55 and hence a person is always liable to scald him or her self whenever the bag has to be filled with hot water.

In order to do away with this great inconvenience I entirely dispense with the usual flexible strap, and attach to one or both of the edges of the bag, just below its neck, the handle or handles I, which are made of any rigid material. These handles may be formed of the shape here shown, or any other that may be preferred, so 65 that they are readily grasped, and serve to hold the bag with safety while being filled or carried around afterward. As here shown, the handles are made of stiff wire, and are covered with rubber and attached to the bag during its manufacture, so that when the bag is vulcanized the handles become a rigid part thereof. Hard rubber or any analogous material having the requisite amount of strength and rigidity may be used instead of the wire.

70 Should it be desired to make the handles entirely out of metal, the bag will be provided with a metallic neck and the handles be formed with or secured to the neck in any suitable manner.

I do not limit myself to any special manner of making or attaching the handles, as they may be varied in a number of ways without departing from the spirit of my invention.

Having thus described my invention, I 85 claim—

A flexible water-bag provided with one or more rigid handles, whereby the bag can be safely held while being filled or used for other purposes, substantially as shown.

In testimony whereof I affix my signature in presence of two witnesses.

MORRIS MATTSON.
